US00D961387S

(12) **United States Design Patent** (10) Patent No.: **US D961,387 S**
 Milan (45) Date of Patent: ** *Aug. 23, 2022

(54) **BEVERAGE CONTAINER LID**

- (71) Applicant: **Enterprise Express, Inc.**, Bethesda, MD (US)
- (72) Inventor: **Michael Milan**, Bethesda, MD (US)
- (73) Assignee: **Coollid Corporation**, Irvine, CA (US)
- (*) Notice: This patent is subject to a terminal disclaimer.
- (**) Term: **15 Years**
- (21) Appl. No.: **29/639,945**
- (22) Filed: **Mar. 9, 2018**
